CLAIM

The ornamental design for a tape recorder, as shown and described.

DESCRIPTION

FIG. 1 is a top, front and right side perspective view of a tape recorder showing my new design;
FIG. 2 is a right side elevational view thereof;
FIG. 3 is a left side elevational view thereof;
FIG. 4 is a rear elevational view thereof;
FIG. 5 is a front elevational view thereof;
FIG. 6 is a top plan view thereof;
FIG. 7 is a bottom plan view thereof; and,
FIG. 8 is a top, front and right side perspective view thereof.

The broken line showing of the toilet in FIG. 8 is for illustrative purposes only and forms no part of the claimed design.

FIG. 8

FIG. 1

FIG. 2

FIG. 4

FIG. 6

FIG. 5

FIG. 7

FIG. 3
